SWITCH STRUCTURE

Malcolm E. Henning, Des Moines, Iowa, assignor
to Penn Electric Switch Co., Des Moines, Iowa,
a corporation of Iowa

Application March 25, 1932, Serial No. 601,124

1 Claim. (Cl. 62—4)

One object of my invention is to provide an automatic control switch structure including a pair of switches responsive to different conditions and constructed in a simple, durable and inexpensive manner.

A further object is to provide in a switch structure, a safety device for moving one of a pair of switches to off position, the safety device being operable independent of the normal automatic means which actuates the other switch.

Still a further object is to provide a switch structure for controlling an electric circuit, including a pair of switches series connected with each other, automatic means being provided for controlling one of said switches according to normal conditions and the other switch being in the form of a safety switch to operate upon occurrence of abnormal conditions only, it normally being unaffected and remaining in closed position.

20 A further object is to provide an automatic switch structure having a pair of switches, each of which is constrained to closed circuit position by magnetic means, with a pair of actuating mechanisms responsive to different conditions, one condition normal and the other abnormal for operating the switches independent of each other.

More particularly it is my object to provide a switch structure to be used for instance in a refrigerating system where means controlled by the 30 temperature of the refrigerant automatically actuates one of the switches, while the pressure of the refrigerant itself may actuate the other switch, thereby providing a safety means for discontinuing the electric circuit upon abnormal conditions occurring. Thus though temperature conditions call for continued operation of a refrigerant motor and compressor, an abnormal condition, such as clogging of the refrigerant pipes, may operate the other switch to prevent 40 such operation of the motor.

This causes a shut-down of the refrigerating system until the pipes are cleaned out and thus again put in condition for proper operation of the refrigerating system.

45 With these and other objects in view my invention consists in the construction, arrangement and combination of the various parts of my device, whereby the objects contemplated are attained, as hereinafter more fully set forth, pointed 50 out in my claim, and illustrated in the accompanying drawing, in which:

Figure 1 is a side elevation of a switch structure embodying my invention and showing it diagrammatically connected with a refrigerating system.

Figure 2 is a reverse enlarged side elevation of the switch structure, showing part of the structure broken away and other parts in section.

Figure 3 is a sectional view on the line 3—3 of Figure 2; and

Figure 4 is a sectional view on the line 4—4 of Figure 3.

On the accompanying drawing, I have used the reference numeral 10 to indicate a switch casing. Pivoted on a pin 12 therein is a main switch arm 65 14 and a safety switch arm 16. The switch arms 14 and 16 carry contacts 14a and 16a respectively for engagement with stationary contacts 14b and 16b. The contacts 14a and 16a are loosely mounted relative to the arms 14 and 16 and are 70 carried by leaf springs 18.

Magnets 20 and 22 exert pull on the switch arms 14 and 16 to normally constrain them toward closed circuit positions.

The contact 14b is electrically connected with 75 a terminal 14c, while the contact 16b is electrically connected with a terminal 16c.

The pin 12 serves as an electrical connection between the arms 14 and 16 so that the arms are connected in series with the terminals 14c 80 and 16c and thus in series with any electrical circuit connected with the terminals.

The main switch arm 14 is operated by a temperature responsive bellows 24 opposed in its action by a spring 26. A knob 28 is provided for 85 adjusting the tension of the spring 26, but forms no part of my present invention. The bellows 24 and the spring 26 operatively engage a lever 30 pivoted at 32 and having its opposite end hooked over a bail 34 which pivotally extends 90 through an opening 35 in the arm 14.

From the construction of the parts just described, it will be obvious that a pressure or temperature decrease applied to the bellows 24 will permit the spring 26 to swing the lever 30 downwardly and thus exert a pull on the switch arm 14 to separate the contact 14a from the contact 14b when such pull is sufficient to overcome the magnetic pull of the magnet 20 on the arm 14.

In Figure 1, I have shown a refrigerator 100 with a piping connection 38 between the bellows 24 and the interior of the refrigerator, so that the temperature in the refrigerator will automatically affect the bellows 24 and operate the switch arm 14.

105 The safety switch arm 16 is operated by a bellows 40 in the following described manner. An arm 42, preferably of insulation, is pivoted at 44 and has a slot 46. The slot 46 receives a finger 48 of a lever 50 also pivoted on the pin 110

44. The lever 50 is of spring construction and has a resilient arm 52 adapted to engage the safety switch arm 16, as best shown in Figure 4. It will thus be obvious that upward pressure on the right hand end of the lever 42 sufficient to overcome the pull of the magnet 22 on the arm 16 will separate the contact 16a from the contact 16b. The spring 52 will first be tensioned so that when separation does occur, it will occur 10 with a snap action.

The bellows 40 is supported within a casing 54, which may be secured in any suitable manner to the switch casing 10. A lever 56 has pintles 58 extending through the casing 54 to provide 15 a pivotal connection for the lever to the casing. The opposite end of the lever 56 engages the lever 42. A slot 59 in the casing 54 is provided as a stop for the lever 56, the lever having a finger 60 extending through the slot.

20 It will be obvious that pressure within the bellows 40 will raise the lever 56 and such raising is opposed by a spring 62. The tension of the spring 62 may be adjusted, a screw 64 and lock nut 66 being provided for this purpose.

25 By means of piping 68, the bellows 40 may be connected with the piping 70, for instance, of the refrigerating system. The refrigerant compressor is indicated at 72 and the electric motor for driving it at 74. It will be noted that the 30 motor is wired in series with the switches 14 and 16.

Practical operation.

35 Referring to Figure 1, normal operation of the refrigerating system will cause lowering of the temperature in the refrigerator 36 until the bellows 24 has collapsed sufficiently to allow the spring 26 to separate the contact 14a from the contact 14b. Thus the electric circuit to the motor 74 is broken so that operation of the compressor 72 is stopped and thereupon the refrigerator 36 will gradually warm up until such time as the bellows 24 has expanded sufficiently to permit the magnet 20 to pull the switch arm 14 to closed circuit position. Thus normal automatic starting and stopping of the refrigerating mechanism is effected.

40 Abnormal conditions occur sometimes, such as clogging of the pipes 70 or any of the other pipes of the refrigerating system and in such event, 45 the main switch 14 may be closed because of the

temperature condition of the refrigerator 36 being high, but it is nevertheless desirable to stop the refrigerating system to prevent damage thereto until the pipes have been cleaned out, or the difficulty otherwise remedied. Upon such clogging occurring, excessive pressure will be built up in the pipe 68 and consequently in the bellows 40. This will raise the lever 56 and the lever 42 for causing the spring 52 to first exert tension on the safety switch arm 16 and then separate the contact 16a from the contact 16b against the action of the magnet 22. Thus the electric circuit will be broken upon abnormal pressure conditions and the switch 16 accordingly acts as a safety switch.

50 The bellows 40 is opposed by the spring 62 so that normally the stop finger 60 engages the bottom of the slot 59, but when excessive pressure is built up, the pressure overcomes the tension of the spring 62 to operate the safety switch.

55 The pressure at which the safety device will operate may be predetermined by adjusting the screw 64, so that if the safety device is to operate only at a very high pressure, the tension of the spring 62 can be increased, while if the safety 100 operation pressure is to be low, the tension of the spring 62 may be decreased.

60 Some changes may be made in the construction and arrangement of the parts of my device without departing from the real spirit and purpose of my invention, and it is my intention to cover by my claims, any modified forms of structure or use of mechanical equivalents, which may be reasonably included within their scope.

65 I claim as my invention:

Refrigerating mechanism comprising a compressor, electric power means therefor, a cooling chamber, an evaporator therein, a high pressure conduit and a low pressure conduit connecting said compressor with said evaporator and a switch 115 structure, said switch structure comprising a pair of switches series connected with each other and with said power means, magnetic means tending to close each of said switches, means actuated by the temperature condition within said cooling chamber for opening one of said switches and means actuated by the pressure condition in said high pressure conduit for opening the other of said switches.
